UNITED STATES PATENT OFFICE.

CHARLES T. BRENNAN, OF WATERBURY, CONNECTICUT, ASSIGNOR TO THE E. J. MANVILLE MACHINE COMPANY, OF WATERBURY, CONNECTICUT, A CORPORATION OF CONNECTICUT.

BLANK-FEED MECHANISM.

1,180,903.

Specification of Letters Patent. Patented Apr. 25, 1916.

Application filed September 17, 1915. Serial No. 51,178.

To all whom it may concern:

Be it known that I, CHARLES T. BRENNAN, a citizen of the United States, residing at Waterbury, in the county of New Haven and State of Connecticut, have invented a new and useful Improvement in Blank-Feed Mechanism, of which the following is a specification.

This invention relates to the mechanism which is provided for automatically picking bolt and screw blanks from a promiscuous mass in a hopper and feeding them in correct position to the operating tools of such machines as headers, screw slotters, screw thread rollers, bolt threaders, bolt pointers and bolt trimmers. The blanks to be operated upon in such machines are thrown into a hopper and by an elevator are picked up and delivered to a raceway down which it is desired that they shall flow in a continuous stream with all of their heads up and in line, and their shanks hanging down parallel with each other. Frequently, particularly with large and heavy machine screw and bolt blanks, the blanks are lifted by the elevator crosswise or otherwise so misplaced as to interrupt the flow of blanks down the raceway. This impairs efficiency as during the interruption of the feed the machine runs idle, that is, the operating mechanisms, while actuated, have no blanks to operate upon. Numerous mechanisms have been designed for clearing the elevator and raceway of these misplaced or unruly blanks and on certain classes of work these have operated successfully, but on other work, such as the handling of large and heavy blanks, they have failed to operate satisfactorily.

The object of this invention is to provide the automatic feeds of machines of this character with blank clearance mechanism which is actuated in such manner that it will remove misplaced and unruly blanks of all sizes, particularly those of the larger and heavier sizes, so surely and quickly that the flow of blanks to the operating mechanisms of the machine will be uninterrupted. To attain this end a comb is arranged to be continuously reciprocated longitudinally along the upper end of the raceway in the hopper, at much greater speed than the reciprocations of the elevator, in such a way that it will knock off from the elevator and back into the hopper all misplaced or unruly blanks before they have time to interfere

with or interrupt the flow down the raceway.

Figure 1 of the accompanying drawings shows a side elevation of a blank feed mechanism constructed according to the invention. Fig. 2 shows a plan of the hopper and feed mechanism. Fig. 3 shows an elevation looking at the opposite side of the hopper and feed mechanism from that shown in Fig. 1. Fig. 4 shows a vertical section on the plane indicated by the dotted line 4—4 on Fig. 2. Fig. 5 is a view looking at the face of the clearing comb. Fig. 6 is a side view of the bracket, and face view of the crank which reciprocates the comb.

The blanks are thrown indiscriminately into the hopper 1. Those blanks which happen to be in available position are picked from the promiscuous mass in the hopper and lifted by the elevator 2 which, in the form shown, consists of two plates fastened together at a distance from each other so that the shanks of the blanks will hang down between them as their heads are caught and carried up by the upper edges. The elevator plates are secured to a lever 3 which is mounted on one end of a shaft 4. On the other end of this shaft is a rocker arm 5 which by a link 6 is connected with a crank 7 that is attached to a gear 8. Meshing with this gear is a pinion 9 on the main shaft 10 which carries the driving pulley 11. By this mechanism the elevator is lowered down to the bottom of the hopper and then raised until the upper edges of the plates are in line with the plates of the inclined raceway 12. The raceway plates, which are spaced apart as are the elevator plates, are secured to the outside of the hopper and extend through an opening in the front wall on such an angle that the raised blanks hanging by their heads will slide down the elevator and along the raceway through the front wall of the hopper.

In the hopper at the upper end of the raceway is a comb plate 13. This comb plate has an opening through it which will allow the passage of the heads of those blanks that are properly located, that is, which are hanging by their heads on the elevator, but will not permit the passage of blanks lifted crosswise, or otherwise misplaced. The comb plate is attached to the end of an arm 14 which is connected with the lever 15 that is pivoted to the bracket 110

16. This lever is slotted and movable in the slot is a block 17 mounted on a crank pin 18 that projects from a disk 19 on the end of a shaft 20. At the outer end of this shaft is a pulley 21 which is connected by a belt 22 with a pulley 23 on the main driving shaft. This crank mechanism rapidly reciprocates the comb along the top edge at the upper end of the raceway, and as the 10 comb reciprocates very fast it knocks away from the upper end of the raceway, while the elevator is down, all misplaced or unruly blanks which have been brought up, so that the raceway is always clear to receive from the elevator the blanks that are 15 properly located to slide down and out of the hopper to the forming mechanisms of the machine to which the automatic feed is applied.

20. The invention claimed is;

1. In an automatic blank feed the combination with a hopper and a raceway leading therefrom, of an elevator adapted to be lowered and raised in the hopper, mechanism including a rotatory crank for lowering and raising the elevator at a moderate speed, a comb adapted to be reciprocated at the upper end of the raceway, mechanism including a rotatory crank for rapidly reciprocating the comb, and driving mechanism arranged to actuate the elevator crank mechanism and the comb crank mechanism. 25

2. The combination with a hopper of an automatic blank feed, of an elevator with an inclined lifting edge adapted to be re- 30

35

ciprocated up and down in the hopper, mechanism for reciprocating the elevator at a moderate rate of speed for lifting the blanks, a comb adapted to be reciprocated adjacent to the lower edge of the elevator for knocking away blanks which are improperly lifted by the elevator, mechanism for reciprocating the comb faster than the reciprocation of the elevator, and driving mechanism for actuating the elevator reciprocating mechanism and the comb reciprocating mechanism. 40

45

3. In an automatic blank feed the combination of a hopper with a raceway leading therefrom and an elevator reciprocating therein, a comb movable in the hopper along the upper end of the raceway and adjacent to the elevator, and mechanism for reciprocating the elevator slowly and the comb rapidly. 50

4. In an automatic blank feed the combination with a hopper and a raceway leading therefrom, of an elevator, mechanism including a rotatory crank for reciprocating the elevator in the hopper, a comb movable along the upper edge of the raceway, a crank mounted upon the hopper, a link connection between the crank and the comb, driving mechanism for rapidly rotating the comb crank, and speed reducing mechanism between the driving mechanism and the elevator crank, whereby the elevator is raised and lowered slowly and the comb is reciprocated rapidly. 55

CHARLES T. BRENNAN.
